FLOOR CONSTRUCTION

Robert H. Carson, Arlington, Mass., assignor to
the Government of the United States

Application February 3, 1945, Serial No. 576,116

3 Claims. (Cl. 20—8)

1

This invention relates to an improved floor construction and more especially to a floor construction for receiving and concealing electrical wiring and other materials.

An object of the invention is to provide an improved floor construction and to devise means for placing wires, cables, and the like beneath the surface of a floor to prevent such members from becoming entangled with one another. Another object is to dispose of a relatively large number of conductor wires so as to provide an unobstructed floor area. It is also an object of the invention to provide a floor construction which permits ready accessibility throughout the floor so that wires may be quickly and efficiently taken up, repaired or examined at any given point without removing or altering the floor construction at other points. Other objects will appear from the following description of the drawing.

In the accompanying drawing:

Fig. 1 is a fragmentary plan view of the floor construction of the invention; and

Fig. 2 is a cross section taken on the line 2—2 of Fig. 1.

The invention generally includes a floor construction which is formed of sections or squares of flooring, detachably secured over floor timbers by means of plate members. The plates are arranged at points of intersection of transversely extending timbers, and longitudinally extending timbers on the upper edges of these timbers. The size of the plates is designed to present four projecting corners. The sections or squares are secured to these projecting corner portions by means of fasteners, with each section or square fastened at its four corners. At some convenient point the floor timbers are recessed to provide openings through which conductor or cable members may extend, lying just below the sections or squares in a convenient position for inspection or repair at any given point corresponding to one of the floor squares.

Referring more in detail to the drawing, numeral 10 denotes floor timbers or joists which are arranged in spaced relation, extending transversely as viewed in Fig. 1 of the drawing. Similarly, numeral 12 denotes other floor timbers or joists which extend longitudinally as viewed in Fig. 1 of the drawing. Preferably a supporting surface for the joists or boards, or other rough flooring material 11 is provided, as shown in Fig. 2. The joists in turn support a plurality of squares of flooring material 13.

The squares are secured to plates 14 which are solidly secured by fastenings 15 on the upper

edges of the floor timbers at points of intersection thereof. These plate members are preferably formed with a square shape and are of a size such that they exceed the width of the floor timbers 10 and 12, thus providing projecting corner portions, as may be more clearly observed in Fig. 1. The projecting corner portions are provided with openings 16 which are adapted to receive screw fasteners 17, which are formed with lug portions 18 and may, upon a half rotation, be engaged with a second fastener piece 19, attached at the under side of the plate. If desired, other types of fasteners may be resorted to.

The joists 10 may be cut away at some convenient point, as for example midway between two adjacent longitudinally extending joists 12, and at the upper edge thereof, to provide an opening 20. In this opening may be placed a plurality of electrical conductors 21, as may be more clearly observed in Fig. 2. If desired, a plurality of openings may be provided for in the floor timbers and these openings may be formed in the longitudinally extending joists as well as in the transversely extending joists.

The construction described thus permits the conductor wires 21 to be located below the surface of the floor. This is particularly advantageous in connection with the use of a relatively large number of pieces of electrical apparatus where a great many conductor wires are required, and by so doing unobstructed floor area is obtained. The projecting corner of the plates used to secure four corners of a square of floor material provides easy access to these conductor members at any point along the floor since the screw fasteners 17 may be disengaged by a half turn and the squares lifted away from the plates. Any number of sections may be removed at a given time, but it should be observed that where a particular section of the wiring is desired to be inspected, this may be carried out without altering or changing adjoining sections of the surface flooring.

It will be seen that I have provided an improved floor construction which is particularly adapted for use in concealing a large number of electrical conductors and maintaining an unobstructed floor area. At the same time, flexibility in removing or examining sections of electrical conductors is provided for, and such conductors are readily accessible at all points.

While I have shown a preferred embodiment of my invention, it should be understood that various changes and modifications may be resorted to,

3

in keeping with the spirit of the invention as defined by the appended claims.

I claim:

1. An improved floor construction comprising supporting members arranged crosswise with respect to one another, plates fixed to the supporting members at intersection points thereof and being of a size adapted to present corners projecting beyond said intersection points; and squares of surface flooring material detachably secured to the corners of said plates.

2. An improved floor construction for receiving and concealing electrical wires, comprising intersecting floor timbers having their upper edges recessed to receive electrical wiring therein, a plurality of plate members fixed to the timbers at points of intersection thereof, said plates being of a size exceeding the width of the timbers to present projecting corner portions projecting beyond said points of intersection, the corner portions of said plate members being formed with

5

openings, squares of finish flooring provided at the corners thereof with fastening members adapted to extend through the openings in the plates and lock at the under side thereof.

3. An improved floor construction for receiving and concealing electrical wires, cables and the like, comprising a plurality of squares of flooring materials arranged with edges thereof adjoining one another to present a substantially continuous surface, said squares being formed at their corners with openings, fastening members extending through the said openings to detachably secure said squares of flooring material to underlying floor timbers, plate members fixed to the floor timbers adapted to receive said fastenings extending through the corners of squares of flooring material, and said timbers being recessed to provide slots through which electrical wires may extend.
